UNITED STATES PATENT OFFICE.

PETER BOYD, OF PITTSBURGH, AND AUGUSTUS M. SAUNDERS, OF MCKEESPORT, PENNSYLVANIA, ASSIGNORS TO THE NATIONAL TUBE COMPANY, OF PITTSBURGH, PENNSYLVANIA, A CORPORATION OF NEW JERSEY.

WELL-SINKING APPARATUS.

1,141,927.

Specification of Letters Patent.

Patented June 8, 1915.

Application filed November 17, 1911. Serial No. 660,846.

To all whom it may concern:

Be it known that we, PETER BOYD and AUGUSTUS M. SAUNDERS, both citizens of the United States, residing at Pittsburgh 5 and McKeesport, respectively, in the county of Allegheny and State of Pennsylvania, have invented certain new and useful Improvements in Well-Sinking Apparatus, of which the following is a specification.

10 Our invention relates to the means employed in forming bored wells by what is known as the hydraulic rotary system in which system the well casing is provided with a cutting head or cutting bit on its 15 lower end and is turned or rotated during its descent into the well as the depth of the opening or hole is increased during the well sinking operations.

Heretofore, with the hydraulic rotary system of sinking both shallow and deep wells, it has been the universal practice to employ a casing which is cylindrical in cross section, a cutting head or drill bit which is slightly larger than the diameter of the casing 25 being attached to the lower end of the lowermost section of the casing. Water, under considerable pressure, is forced into the hollow casing through a swivel head detachably secured so as to be rotatable on the 30 upper end of the casing while the casing is being turned, and issuing from the lower end of the casing is forced upwardly in the small annular space between the earth wall of the hole and the outer surface of the casing. The stream of water, in rising between the casing and earth wall of the well washes or carries all of the loosened earth or other material dislodged by the cutting head or bit, upwardly out of the well to the surface. 35

40 In sinking wells with cylindrical casings which are freely movable lengthwise, the turning mechanism frictionally engages the surfaces of the casing, and the sharp edges of the turning mechanism, having a point or 45 line contact with the surface of the casing, dig or bite into and cut deep grooves or channels in the casing. The casings, when grooved or scored in this manner, are weakened to such extent as to frequently split or

break, which is the cause of frequent delays 50 in the well sinking operations and a source of great expense in removing and replacing the damaged sections of the well casing. It is also necessary with the cylindrical casing used heretofore, to retract the gripping 55 mechanism when engaged by the couplings connecting the ends of the sections of casing on account of the larger diameter of these couplings.

One object of our invention is to provide 60 improved apparatus for forming or sinking such wells having novel means whereby the clearance or area of the opening between the earth wall and outer surface of the casing is increased, the removal of the earth and 65 finely divided solids from the hole or opening is facilitated and more readily accomplished, while the openings or holes are drilled straighter, liability of breakage or other damage to the wall casing is prevented 70 and overcome and a stronger and more durable construction is provided.

Another object of our invention is to provide 75 a well sinking apparatus having novel means for rotating the casing by the use of which the casing is positively turned or rotated and splitting or other damage to the casing is avoided and overcome, and having novel means whereby the casing is rotated 80 during the intervals the rotating mechanism is in engagement with the connected ends of two adjacent sections of the casing, in the passage lengthwise of the joints or connected ends of the casing sections through the rotating mechanism. 85

Referring to the accompanying drawings forming part of this specification, Figure 1 is a side elevation of a portion of a drilling rig showing hydraulic rotary well sinking apparatus constructed and arranged for use 90 in drilling wells in accordance with this invention. Fig. 2 is a plan showing, on an enlarged scale, a detail of the preferred form of driving mechanism by which the well casing is positively rotated in the well forming 95 operations. Fig. 3 is an end elevation of the apparatus shown in Fig. 2. Fig. 4 is a detail in sectional elevation of the chuck

construction forming part of the turning apparatus shown in Figs. 1 to 6. Fig. 5 is a detail plan showing in closed position the construction of the hinged jaws forming part of the sliding connection between the casing and the chuck on the turning mechanism. Fig. 6 is a plan showing the apparatus of Fig. 5 in open or disengaged position. Fig. 7 is a sectional elevation showing 5 a modification in the construction of the casing turning mechanism shown in Figs. 1 to 6, as arranged in accordance with our invention. Fig. 8 is a plan, the casing being in transverse section and Fig. 9 is a side elevation showing a modification in the construction of the turning apparatus. Fig. 10 is a similar plan and Fig. 11 is a side elevation showing a further modification in the construction and arrangement of the parts 10 forming the casing turning mechanism. Fig. 12 is a detail longitudinal section showing one form of coupling for the square casing forming part of this invention. Fig. 13 is a transverse section through the joint of 15 the coupling shown in Fig. 12. Figs. 14 to 20 are views similar to Fig. 12 showing modifications in the coupling means employed in connecting together the abutting ends of two adjoining casing sections in accordance with our invention. Figs. 21 to 27 20 are transverse sections similar to Fig. 13 showing further modifications in the construction of the joints or coupling means illustrated in Figs. 14 to 20, as made in accordance with our invention.

In the drawings, referring to Figs. 1, 2 and 3, 2 designates the base plate of the turning mechanism by which the well casing is rotated which is mounted upon suitable timbers forming the sills 3 of a derrick 4. Rotatably mounted on the base plate 2 is a bevel gear 5 having an annular axially projecting extension on one side forming a hub 6 by which the gear 5 is rotatably mounted in the 40 bearing formed in the base plate 2. This extension or hub 6 is provided at an intermediate point in its length with a peripheral recess 7 and the upper end 8 of the projection is made hexagonal in cross section for a 45 purpose described later. The horizontal upper surface of the base plate 2 has a circular flange 9 which projects upwardly to form a seat for one race ring 10 of the ball bearing mounted on the base plate 2. A split flange 55 11 made in halves is bolted together in place with the inner surface defining the bore of this flange 11 extending into the peripheral recess 7 on the hub 6 and the opposing race ring 12 of the ball bearing surrounds the 60 projecting hub or extension 6 on the gear 5, being maintained in position by engagement with the split flange 11. Balls 13 are mounted in place between the opposing race rings 10 and 12, as is shown in Fig. 1 to form with

the race rings an anti-friction or ball bearing for the gear 5 in the base plate 2.

Mounted in bearings 14 which are secured in place on the sills 3 of the derrick is a horizontal shaft 15 having on one end a bevel pinion 16, the teeth of which are in mesh 70 with the teeth of the bevel gear 5. The outer edge of the gear 5 is arranged to contact with an anti-friction thrust roller 17 which is permanently mounted in the recess for that purpose in the base plate 2 on the 75 pin 18 secured to the base plate 2. The opposite end of the shaft 15 is connected by any desired means to a driving motor (not shown) by which the rotating mechanism forming part of the well sinking apparatus 80 is actuated in the well forming operations.

On the upper end of the hub extension 6 of the gear-wheel 5 is a chuck 19 which is divided axially or lengthwise, the two halves of which are hinged together by means of 85 pins 20, one of these pins having a reduced portion 20^a by which it is secured in the boss 21 on the top surface of the split ring or flange 11 forming part of the turning mechanism. The hinged sections of the chuck 19 90 are detachably secured together in operative position on the hub 6 of the gear 5 by means of an eye bolt 22 pivoted to one section of the chuck. The other section of the chuck has flanges 23 forming a slotted opening into 95 which the opposite end of the eye bolt is located when holding the meeting edges of the chuck sections together. A cam 24 having a handle 24^a by which it is operated is pivoted to one end of the eye bolt 22 to afford means 100 for quickly securing together and releasing the hinged sections of the chuck.

The hinged sections of the chuck 19 are hollow, the upper portion of the opening thereon, as shown, being rectangular in cross 105 section. The lower portion 19 of the axial opening in the chuck, when in closed position, is hexagonal in cross section and embraces the hexagonal outer end 8 of the hub or extension 6 on the gear 5 whereby the 110 chuck is positively turned or rotated with the gear 5 in the operation of the turning mechanism.

Movably secured in the upper portion of the axial opening in the chuck are two plates 115 forming opposing jaws 25, 25, each having a V-shaped recess 26 in one edge thereof. The jaws 25 are of such size as to be freely movable vertically in the chuck 19 when the halves of the chuck are secured together in 120 closed position and the opening formed by the notches 26 in the opposing edges of the jaws 25 is arranged to surround and adapted to engage with the surfaces of and rotate the square casing 27 when the parts are assembled in operative or casing turning position. Eye bolts 25^a secured on the jaw plates 25 and extending through slotted openings in 125

the top end of the chuck 19 are employed in lifting the jaw plates from the bottom to the top of the opening or recess in which they are loosely mounted as is more fully described hereinafter.

In the modification shown in Fig. 7 the clutch on the top of the rotating gear 5 is dispensed with and a hollow sleeve 42 having a rectangular opening therein is secured in the rectangular axial opening in the hub of the gear 5, being held in place by means of a cap screw 43. This construction is adapted for use in cases where the diameter of couplings for the square casing is less than or does not greatly exceed the short diameter of the casing such as for example the coupling constructions shown by Figs. 15 to 20, and 22 to 27. The sleeve 42 is made somewhat greater in length than the length of the couplings by which the casing sections are connected together, so that the lower end of the upper section of the casing is operatively engaged by the surfaces of the recess or opening in the sleeve 12 before the upper end of the adjacent section of casing is entirely clear of the sleeve.

In the modified form of turning mechanism shown in Figs. 8 and 9, anti-friction rollers 30 are adjustably secured on horizontally extending rods or shafts 29, these shafts being provided with a series of disk washers 28 to permit the anti-friction rollers 30 rotatably mounted thereon to be adjusted axially and brought into operative engagement with opposite side walls of the square casing 27. Disk guides 31 contact with one face of each anti-friction roller 30 to provide means for guiding and holding the casing 27 in position while moving downwardly during the well forming operation. The shafts 29 for the anti-friction rollers 30 are mounted in swivel bearings 32 which in turn are adjustably mounted on the transversely extending screw threaded bars 33, screw threaded nuts 34 having hand wheels 35 thereon being mounted in the swivel bearings 32 on the opposite ends of the transverse threaded bars 33 to permit of side-wise adjustment being made. The transversely extending threaded bars 33 are pivoted intermediate of their ends on pins 33^a to the upper face of a bevel gear 37 rotatably mounted upon the base plate 38, and the teeth of a bevel pinion 39 mesh with the teeth of and drive the bevel gear 37. A horizontally extending drive shaft 40 in bearings 41 has the bevel pinion 39 secured on one end thereof, the other end of the shaft 40 being connected to a suitable motor or other prime mover (not shown).

In the apparatus shown in Figs. 10 and 11 a modification of the apparatus shown in Figs. 8 and 9 is shown. The arrangement of the bevel gears 37 and 39 on the base

plate 2 is the same as in Figs. 8 and 9, and 65 the manner in which the anti-friction rollers are mounted on the bevel gear 37 is similar. In this construction but one anti-friction roller 44 is used on each side of the axis of the casing, the periphery of these anti-friction rollers each having a V-shaped groove or recess 45 therein which engages with two adjacent sides of the square casing 27 in rotating the casing when the turning mechanism is in operation. As will be seen by 70 reference to the drawings the body of the pipe or tube sections 27 forming the casing is rectangular in cross section with integral cylindrical screw threaded end portions 27^a.

As shown in Figs. 12 and 13 and also in 80 Figs. 14 and 21, the cylindrical ends 27^a are thickened by upsetting or by welding a collar thereon and a screw threaded coupling 46 is employed to connect the abutting ends of the adjoining casing sections. The outer 85 diameter of the cylindrical end portions 27^a is approximately the same as the short diameter or width of the rectangular body of the casing.

In Figs. 15 and 22 the cylindrical end 90 portions 27^b are reduced in diameter and are screw threaded to receive the couplings 46, the outside diameter of the couplings being approximately the same as the short diameter or width of the body of the casing 95 sections.

In Figs. 16 and 23 a construction is shown in which a nipple 47 is employed to connect the abutting cylindrical end portions 27^c of adjoining casing sections and in Figs. 100 17 and 24 the connecting nipple 47 is the same, the outer surface of the ends 27^c of the casing sections being rectangular in cross section, so that the cross section of the casing sections is rectangular for their entire 105 length.

As shown in Figs. 18 and 25 the ends 27^d, 27^e of the casing sections are cylindrical and one end 27^d of each section is reduced in diameter and externally threaded. The cylindrical opposite end portion 27^e of each casing section is provided with internal threads to receive the externally threaded end of the adjacent section so that the coupling is dispensed with.

In Figs. 19 and 26 a construction is shown which is similar to that of Figs. 18 and 25 in having one end 27^f of the casing sections threaded internally and in having the opposite end 27^g of each section cylindrical 120 and reduced in diameter with external threads thereon, and differs from that of Figs. 18 and 25 in having the outer surface of the one internally threaded end 27^f of each section rectangular in cross section, instead of being cylindrical.

In Figs. 20 and 27 the casing sections, when connected together are of the same

rectangular cross section throughout. One end 27¹ of each section is increased in thickness and is provided with internal screw threads, the other end of each section having a reduced screw threaded portion 27² adapted to engage the internal screw threads of the adjoining section of the casing.

In the operation of apparatus constructed as shown in Figs. 1 to 6, the chuck is secured in place on the upper end of the bevel gear, with the jaw plates 25 operatively engaging the lower end of the casing. The bevel gear 5 is then caused to rotate and through the chuck and casing engaging jaw plates the casing is caused to rotate, and as the casing is rotated it descends and gradually enters into the earth as the well is deepened by the cutting action of the cutting head. When the casing is rotated, water under considerable pressure is forced through the casing from the opening or openings in the lower end thereof and is caused to rise between the outside of the casing and the earth wall of the well. As the water rises the finely divided solids loosened and broken up by the cutting head or drill bit are washed upwardly to the surface and out of the well in the usual manner. The corners of the square casing act as a reamer upon the earth walls of the drilled hole or opening during the drilling operation and causes a straighter hole to be formed than when cylindrical casings are employed. As the upper end of the last section of casing to be placed in position reaches a point adjacent to the chuck during its downward movement, a new section of casing is coupled thereto and after the swivel head is connected to its upper end to supply water thereto, the turning operation is continued. When the adjacent ends of two sections of casing approach or reach the position in the chuck shown in Figs. 1 and 6, the chuck is opened into its disengaged position as shown in Fig. 4 and through the medium of the eye bolts 25¹ the jaw plates 25 mounted in the chuck are lifted to the upper end of the recess in the chuck when the two halves are again closed or moved into the position shown in Figs. 1, 2 and 5, with the jaw plates 25 above the casing coupling connecting the two adjoining ends of the casing sections. The rotating operation is then continued until the upper end of the last coupled section of casing reaches the position shown in Figs. 1 and 6 and the above described operations are repeated.

With the construction shown in Fig. 7 the opening in the sleeve 42 permits the casing to move downwardly lengthwise while at all times rotatively engaging with the casing sections, and as the couplings also pass freely through the sleeve and the

sleeves are made of a length sufficient to engage the connected ends of two casing sections, delays in detaching the turning mechanism from one section and connecting it to another section of the casing, are avoided and overcome.

With the construction shown in Figs. 8 and 9, or 10 and 11, the anti-friction rollers are adjusted by means of the hand wheels 35 on the screw threaded nuts 34 so as to bring the anti-friction rollers 30 or 44 into turning engagement with the section of the casing 27 then extending between the opposing anti-friction rollers. The mechanism is then rotated through the medium of the drive shaft 40 as has been before described.

As will be seen by reference to Figs. 12 to 27, the cross section of the coupling members is substantially the same as the cross section of the square casing and when these couplings are engaged by the anti-friction rollers on the turning mechanism the anti-friction rollers do not need to be moved backward so as to become disengaged to such extent as to not positively rotate the casing.

The clutch jaws which are detachable when employed, may vary in size to suit casing of different sizes, as will be readily understood. The anti-friction rollers are adjustable on the turning mechanism, and when employed are movable toward each other to operatively engage with casings of varying sizes. The hollow sleeves of Fig. 7 are made in various sizes to suit the variety of sizes of casings used.

The advantages of our invention will be apparent to those skilled in the art. By the use of a casing or drill rod which is square in cross section the necessity for frictionally turning the casing or rods is avoided and overcome and the formation of grooves and resultant splitting of the casing or drill rods is avoided and overcome. The area of the opening between the earth wall of the well and the flat sides of the casing is much greater than when a cylindrical casing is employed. The corners of the square casing ream the opening formed by the drill bit and causes the wells to be straighter than when drilled with a cylindrical casing. By the use of our improved casing turning mechanism the turning mechanism has a surface contact with the casing instead of a line contact, as heretofore, and the positive rotation of the casing and the prevention of slippage is made an absolute certainty.

Modifications in the construction and arrangement of the parts may be made without departing from our invention as defined in the claim.

We claim:—

A well sinking apparatus including a rotary and a chuck, and a combined tubular reamer and casing of polygonal cross-sec-

tion, said chuck having angularly-disposed straight bearing faces for loosely embracing and rotating the casing by engaging a plurality of the plane sides thereof with broad 5 bearings against said sides of the polygonal tubular casing, and also permitting endwise movement of the polygonal tubular casing through the chuck, the corners of the polygonal tubular casing operating as a reamer on

the walls of the well during the drilling 10 operation.

In testimony whereof, we have hereunto set our hands.

PETER BOYD.

AUGUSTUS M. SAUNDERS.
